UNITED STATES PATENT OFFICE.

ROBERT K. WINNING, OF WAUWATOSA, WISCONSIN, ASSIGNOR TO CLUM MANUFACTURING COMPANY, OF MILWAUKEE, WISCONSIN.

STOP-LIGHT SWITCH.

Application filed June 1, 1925. Serial No. 34,062.

This invention relates to improvements in stop-light switches.

It is the primary object of this invention to provide a simple and novel type of switch mechanism adapted particularly to lend itself to constructional methods involving stamping operations.

It is particularly the object of the invention to provide a novel type of switch casing adapted to be stamped in two parts and provide in an improved manner a base portion having integral foot flanges for the mounting of the device, an upper portion adapted to facilitate the positioning of switch contacts, and a bearing formed in part from each of the base and upper portions of the casing.

In the drawings:

Figure 1 is a plan view of a switch casing embodying this invention.

Figure 2 is an end elevation thereof.

Figure 3 is a section taken on line 3—3 of Figure 1.

Figure 4 is an enlarged detail section taken on the axial plane indicated by line 4—4 of Figure 2.

Like parts are identified by the same reference characters throughout the several views.

The particular switch illustrated is specifically adapted for use as a switch to control a stop signal on a motor vehicle. It is peculiarly fitted for this service by reason of the fact that the actuating connections are free to move for some distance after the switch has been closed. Such an arrangement is desirable in connection with a stop signal switch for the reason that it is ordinarily desirable to illuminate the stop signal as soon as the brake is applied and some arrangement must be made for permitting the added movement of the brake connections which is necessary for the full application of the brake.

In such an arrangement the movement of the brake or its actuating levers or rods may be communicated to the axially adjustable shaft 5 of the switch. The shaft is flattened at 6 and provided with an aperture 7 to receive connection with the brake mechanism. A split washer 8 applied to shaft 5 is adapted to contact with the switch casing to limit the axial movement of shaft 5 in one direction therethrough. A similar split washer 9 is applied to shaft 5 within the casing to

limit the movement of the shaft in the other direction.

The bearings 10 within which shaft 5 is reciprocable are formed by pressure in the members comprising the switch casing. A switch casing made in accordance with this invention preferably is composed of but two separate pieces 11 and 12.

Casing member 12 is the base section of the casing and comprises an intermediate portion 13 which is cylindrical in contour and terminates in the vertical end portions 14 and the horizontal shelf portions 15. The shelf portion 15 of section 12 of the casing extends completely about the cylindrical wall 13 thereof and projects both laterally and longitudinally therefrom. The metal of which casing section 12 is composed extends beyond the laterally projecting parts of the shelf 15 and is bent downwardly at 16 to comprise legs and laterally at 17 to comprise feet having apertured ears 18 through which mounting screws or bolts may be passed.

The upper casing section 11 is provided with a channel complementary to the cylindrical wall 13. Instead of being cylindrical, however, it is preferably like a broad V in cross section, being composed of two walls 19 and 20 which are substantially at right angles to each other. Integrally with walls 19 and 20 are formed the ends 22 and a circumferential flange 25 which is complementary to the shelf section 15 of the lower casing section and is riveted thereto at 26. The bearings 10, above referred to, are formed by pressing corresponding portions of the shelf flange 15 and of flange 25 in opposite directions, as is clearly shown in Figure 2, so that a cylindrical opening is left between these two flanges.

The purpose of providing the plane wall at 19 and 20 in the cap section 11 of the casing is related to the mounting of the switch contacts and terminals. Each of the walls 19 and 20 is provided with a pair of axially aligned openings 27 and 28. Applied to these walls above and below the openings therein are the correspondingly apertured pieces of dielectric material 29 and 30 which may comprise fiber, rubber, or any other suitable substance for the purpose. Beneath the sheet 29 of dielectric is a flat spring contact 32 having an upturned extremity 33. A tubular rivet 34 is headed at 35 to engage spring 32 and passes therethrough and

through the apertures in dielectric sheets 29 and 30 to engage with a metal washer 37 which is placed exteriorly of dielectric sheet 30. The tubular rivet 34 after passing 5 through the washer 37 is expanded into engagement therewith, whereby to bind the spring rigidly to the cap section 11 of the casing through the interposed dielectric which insulates the spring from the casing. 10 This tubular rivet 34 also comprises a nut into which a terminal screw 38 may be threaded as shown in Figure 4. A second rivet 40 headed at 41 for engagement with dielectric sheet 30 passes through the dielectric sheets 30 and 29 and through the 15 flat spring contact 32 and is expanded to bindingly engage this contact. This provides a second point at which the contact is secured and consequently assures the permanency of alignment of the contact. The 20 two contacts and their respective mountings are identical and the arrangement is clearly shown in Figure 4.

The contact closer carried by axially movable shaft 5 is adapted to establish an electrical connection between the contacts 32 and is nevertheless insulated from the switch casing and the shaft 5 which carries it. The contact closer comprises a set of three dielectric washers 43, 44 and 45. Washer 45 is disposed between the other two and is of larger diameter. Applied to its periphery is a channel shaped rim 46 comprising the contact closer. This channel shaped rim has flanges 47 which are turned or spun centripetally into permanent engagement with the central and larger diametered dielectric washer 45. The split washer 9 limits the movement of the three washers 43, 44 and 45 in one direction upon shaft 5 and the three washers are maintained in their proper relation to each other and in contact with the split washer 9 through the medium of a compression spring 50 which seats against the dielectric disk 43 and, at its opposite end, against the washer 51 which abuts the end walls 14 and 22 of the lower and upper casting sections respectively.

The conductors which carry the current 50 from the battery to the switch and from the switch to the light will of course be secured to the fixed spring contacts 32 by means of screws 38. Consequently there will be no necessity for adjustably moving any part to which a wire is connected. The 55 two spring contacts are insulated by the interposed dielectric sheets 29 and 30 from the walls 19 and 20 of casing section 11 and consequently from each other. In the normal 60 retracted position of the moving parts of the switch the heel portions 52 of contacts 32 will rest upon the dielectric disk or annulus 43.

When a pull is exerted on shaft 5 through 65 the eye 7 in the end thereof so that such

shaft is drawn to the left in Figure 4 against the compression of spring 50 it will be apparent that the annular contact closer 46 will immediately encounter the elevated extremity 33 of each spring contact 32. Current will thereupon pass between the spring contact 32 through the movable contact closer 46 but the switch casing and shaft 5 are insulated from such current by means of the dielectric disks 43, 44 and 45 which position 70 and mount the annular contact closer. When the tension exerted on the axially movable shaft 5 is relieved, such shaft is forced to the right in Figure 4 by means of the compression spring 50 and to the extent permitted by split washer 9 which ultimately contacts with the end of the two-part casing.

It will now be apparent that a simple compact device has been provided for the 85 purposes aforesaid and that the particular disposition of the walls 19 and 20 tangential to a common imaginary circle drawn about the axis of shaft 5 of the cap section facilitates the mounting of spring contacts 32 in 90 the desired positions so that the spring contacts will move yieldably in radial axial planes to which their flat surfaces are normal and in a manner which is very economical of space. It must also be obvious to 95 those skilled in the art that the device herein disclosed is not only compact but can be very economically manufactured, inasmuch as the peculiar shape of the casing sections is such that these sections can readily be made 100 by stamping or pressing operations. It will be noted that the end and side walls of the casing are seamless with the exception of the joint between flanges 15 and 25 and the construction is such that if the mechanism 10 is mounted in the usual inverted position upon the underside of the body of the car it will be substantially weather proof.

I claim:

1. As a new article of manufacture, a two-part switch casing comprising a cap section and a mounting section, each of integral construction and pressed from sheet material, said sections having their intermediate facing portions pressed oppositely to provide a 111 chamber, said chamber having end and side walls in each section, the two sections having facing circumferential flanges extending outwardly from the side walls.

2. As a new article of manufacture, a two-part switch casing comprising a cap section and a mounting section, each of integral construction and pressed from sheet material, said sections having their intermediate facing portions pressed oppositely to provide a 112 chamber, said chamber having end and side walls in each section, the two sections having facing circumferential flanges extending outwardly from the side walls, and corresponding parts of the circumferential 113

- flanges at the ends of the sections being oppositely channeled to provide semi-cylindrical bearing halves in each section.
3. As a new article of manufacture, a two-part switch casing comprising a cap section and a mounting section, each of integral construction and pressed from sheet material, said sections having their intermediate facing portions pressed oppositely to provide a chamber, said chamber having end and side walls in each section, the two sections having facing circumferential flanges extending outwardly from the side walls, and corresponding parts of the circumferential flanges at the ends of the sections being oppositely channeled to provide semi-cylindrical bearing halves in each section, said mounting section having a portion of its flange extended to form mounting means for the casing.
4. As a new article of manufacture, a two-part switch casing comprising a cap section and a mounting section, each of integral construction and pressed from sheet material, said sections having their intermediate facing portions pressed oppositely to provide a chamber, said chamber having end and side walls in each section, the two sections having facing circumferential flanges extending outwardly from the side walls, and corresponding parts of the circumferential flanges at the ends of the sections being oppositely channeled to provide semi-cylindrical bearing halves in each section, said mounting section having a flange extension at a right angle to the remainder of the flange forming a mounting means for the casing.
5. As a new article of manufacture, a switch casing comprising two integral sections pressed from sheet material, constituting a base section and a cap section, respectively, said sections having their facing intermediate portions pressed oppositely to form a chamber with end and side walls formed partially in each section, the two sections having facing circumferential flanges extending outwardly from the side walls, the flange on each section being pressed outwardly at each end of the section to provide a semi-cylindrical bearing opening, the side walls of one of said sections being substantially flat and substantially normal to planes drawn axially and radially with respect to a longitudinal axis about which said bearing portions are concentric.
6. As a new article of manufacture, a switch casing comprising two integral sections pressed from sheet material constituting a base section and a cap section respectively, said sections having their facing intermediate portions pressed oppositely to form a chamber with end and side walls formed partially in each section, the two sections having facing circumferential flanges extending outwardly from the side walls, the flange on each section being pressed outwardly at each end of the section to provide a semi-cylindrical bearing opening, the side walls of one of said sections being substantially flat and substantially normal to planes drawn axially and radially with respect to a longitudinal axis about which said bearing portions are concentric, said mounting section having its flange formed with an extension at substantially a right angle thereto to form a mounting leg.

ROBERT K. WINNING.
